UNITED STATES PATENT OFFICE.

MICHAEL C. ENSMINGER AND JOHN W. SMITHAM, OF DENVER, COLORADO.

ORE-CAR.

SPECIFICATION forming part of Letters Patent No. 512,178, dated January 2, 1894.

Application filed April 3, 1893. Serial No. 468,913. (No model.)

To all whom it may concern:

Be it known that we, MICHAEL C. ENSMINGER and JOHN W. SMITHAM, citizens of the United States of America, residing at Denver, in the 5 county of Arapahoe and State of Colorado, have invented certain new and useful Improvements in Ore-Cars; and we do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 Our invention relates to improvements in ore cars, and the object of the improvement is to provide a car of this class whose end door shall open automatically as soon as the car body is lifted to a suitable inclination, and 20 automatically return to the locking position when the car body again assumes the horizontal.

To this end the improvement consists of the features hereinafter described and claimed, 25 all of which will be fully understood by reference to the accompanying drawings, in which is illustrated an embodiment thereof.

In the drawings, Figure 1 is a side elevation of the car, the dumping position of the 30 body being indicated in dotted lines. Fig. 2 is a front end view of the same. Fig. 3 is a top or plan view of the platform, the car body being removed. Fig. 4 is a detail view of the 35 means for locking the car body in the upright position.

Similar reference characters indicating corresponding parts or elements of the mechanism in the several views, let the numeral 5 designate the car body pivoted forward of its 40 center of gravity, to the platform 6 which is mounted on the trucks 7.

As shown in the drawings, the axis of the car consists of the bolts or rivets which pass through the coinciding apertures of counter- 45 part lugs formed on the car body and platform respectively, as indicated at 8.

The car is locked in the upright or horizontal position by means of a bell crank-lever 9 located between the rearwardly projecting 50 bars 10 of the frame-work, which approach each other as they extend backward. Lever 9 is fulcrumed at 12. One arm projects up-

wardly and is provided with a hook which enters the aperture formed in a depending plate 13 attached to the rear extremity of the car 55 body. The other arm of the lever projects outwardly from the fulcrum, and occupies approximately a horizontal position. The lever 9 is provided with a short arm 9^a which extends inward from the fulcrum and engages the 60 lower extremity of a coil spring 14, whose upper extremity bears against a top plate 15 made fast to the bars 10. This top plate is slotted as shown at 16 to receive the upright arm of the lever and to allow said arm the 65 required movement. The top plate 15 is provided with apertured wings or projections 15^a to permit the attachment of the "dead chains" 70 26 which are secured to the track. The object of this connection is to prevent the possibility of the car's going over the dump on steep inclines. The door 17 of the car is pivoted at the top by means of a rod 18 which passes through coinciding apertures formed in lugs 17^a and 5^a respectively with which the 75 door and the sides of the car are provided. The door is provided with lateral projections 17^b which engage the hooked outer extremities 19^a of the arms 19 which are made fast at their inner extremities to the platform 6 by 80 means of bolts or rivets as shown at 19^b or in any other suitable manner. These hooked arms lie outside of the vertical planes of the sides of the car body, whereby the latter is allowed to move freely therebetween, as during the operation of dumping and returning 85 to the horizontal position.

To dump the car, the foot is placed upon the outer horizontal arm of the bell-crank lever which is depressed sufficiently to detach 90 the upper arm of the lever from the depending apertured plate. The car body is then unlocked, but as its center of gravity is located to the rear of its axis, it remains in the horizontal position until its equilibrium is destroyed by lifting upon the handle attached to its rear end, when it at once assumes the inclined or dumping position. As soon as the car body has moved a short distance downward, the door 17 is unlocked from the hooked 95 stationary arms 19 and swings outward on its pivot or axis to the vertical position shown by dotted lines in Fig. 1. When the car body is again moved to the upright position, the 100

movement of the door is reversed, and it returns to the locked position with its lateral projections engaging the hooks of the locking arms.

5 Having thus described our invention, what we claim is—

1. In an ore car, the combination with the platform suitably mounted, of the car body pivoted on the platform and having one end 10 hinged at the top of the car and provided with lateral projections, and the hooked locking arms rigidly secured to the platform of the car, their hooked extremities being adapted to receive the lateral projections of the door, substantially as described.

15 2. In an ore car, the combination with the car body pivoted on a suitable platform and provided with a door hinged at the top, of the

locking arms made stationary with reference to the movement of the car body upon its axis 20 and provided with the hooked extremities adapted to engage the door and lock it in place when the car body is in the upright or horizontal position, substantially as described.

3. In an ore car, the combination with the 25 truck-frame, of a plate attached to the rear extremity thereof, and provided with apertured wings or projections, substantially as described.

In testimony whereof we affix our signatures 30 in presence of two witnesses.

MICHAEL C. ENSMINGER.

JOHN W. SMITHAM.
